FIG. 1

FIG. 2

FIG. 3

INVENTOR
HERBERT M. GRIFENHAGEN
BY *Earvin Leisohne*
ATTORNEY

UNITED STATES PATENT OFFICE

HERBERT M. GRIFENHAGEN, OF NEW YORK, N. Y.

BLOUSE

Application filed December 10, 1928. Serial No. 324,931.

This invention relates to improvements in the construction of a weather shirt or blouse and has reference particularly to a shield arranged in the V-neck of the shirt.

5 The object of my invention is to provide a shield of this character wherein the latter may be worn closed with a collar or open without a collar.

10 A further object of this invention is to provide a shield for a shirt front which is open along the front and which is attached to the shirt except at its lower end, thus leaving an opening through which the depending ends of the wearer's necktie are inserted.

15 Briefly the present invention comprises a type of shirt or blouse which may be worn inside or outside the trousers and with or without the elastic waist band often used in weather shirts of this character.

20 I accomplish these objects by means of the garment illustratively exemplified in the accompanying drawings, in which Figure 1 is a perspective view of my improved shirt; Figure 2 is a front view of the shirt and shield closed; and Figure 3 is a similar view showing the shield open.

25 Referring to the drawings, 10 denotes a shirt or blouse, preferably of the type worn outside the trousers, and 11 a shield arranged inside the front opening of the shirt 10. The front opening of the shirt is straight at its lower end in the manner common to substantially all shirts of this character, one side thereof having simply been brought over the other is attached thereto by buttons 12. At a point well below the neck opening the sides of the point opening separate to form a V-neck 13. The edges 14 of the material along the V-neck are piped or bound to provide a finish.

30 The shield 11 is triangular in shape and is composed of two parts divided along a center line and attachably connected together along the center line by means of buttons 15. The outside edges of the shield 11 project well beyond the piped edges 14 of the shirt front and are attached thereto by rows of stitching 16 which extend at each side of the shirt from the neck opening or shoulder seam to a point well short of the lower end

of the V-opening 13 and from the lower ends of the stitching 16 the shield is free of the shirt proper and merely hangs downwardly. This unattached portion of the shirt 10 and shield 11 affords space through which the 65 lower ends of the necktie 17 may project inside the front of the shirt, as illustratively exemplified in Figure 1.

A suitable neck or collar band 18 is provided at the upper end of the shield and neck 60 opening in the shirt 10. A collar 19 is attached to the collar band 18 in the usual manner if the shield is to be worn closed as shown in Figures 1 and 2, but if the shield is to be worn open as illustrated in Figure 3, the 65 collar band 18 at each side folds over the front of the shirt and forms a relatively deep V-shaped front opening in the shield.

It will be understood, of course, that the shield may be designed of various shapes and 70 may further be made of a material entirely different from that of which the shirt proper is made.

Having now described my invention, what I claim as new and desire to secure by Letters 75 Patent is:

In combination, an open front shirt having the upper portion of said opening V-shaped, an open front V-shaped shield comprising two triangular pieces disposed over the V- 80 shaped opening on the inside of the shirt, said shield projecting beyond the sides of the V-shaped opening and having rows of stitching attaching the opposite sides of both pieces to the body of the shirt along 85 lines extending to points short of the apex of the sides of the V-shaped opening to leave an opening into the shirt.

In testimony whereof he has affixed his signature.

HERBERT M. GRIFENHAGEN.
